DIGESTER FOR MANUFACTURE OF
FERTILIZERWilliam D. Taylor and Edmund W. Voegtlil, East
Orange, and Carl E. Schlosser, Livingston, N. J.

Application June 8, 1949, Serial No. 97,722

5 Claims. (Cl. 34—54)

1

This invention relates to apparatus for producing fertilizer, and more particularly to digesters used in the conversion by bacterial reduction of organic materials into fertilizer.

One of the objects of the present invention is to provide a digester which is of simple construction, and which is capable of being operated with low power consumption.

Another object of the present invention is the provision of a digester which comprises a plurality of decks assembled and arranged for operation in such manner as greatly to simplify the construction of, and facilitate the treatment of the source material in, the digester, and also to effect the treatment of said material in its conversion to fertilizer with optimum results. In connection with this object of the invention, it is an important feature to provide for rotation of certain ones of the decks, while other decks may remain stationary.

Another object of the present invention is to make the several decks of the digester in individual units which are easily transportable and may readily be assembled in final superposed relation at the place of installation of the digester.

Another object of the present invention is to make provisions in the digester for power-rotation of alternate ones of the superposed decks relative to the remaining decks and to arrange plows in the digester so that the alternate driven decks constitute the sole motive force required to mix the material in the several decks and to cause its flow through the digester by the plows therein.

Another object of the present invention is to make provisions for adjusting the pitch of the plows from the outside of the digester, thereby to change the mixing characteristics of the source material in the digester and also the rate at which it travels through the latter.

A further object of the present invention is to make provisions for controlling the flow of air into the various decks of the digester, and also for controlling the exhaust of waste gases and vapors therefrom.

The above and other objects, features and advantages of the present invention will be more fully understood from the following description considered in connection with the accompanying illustrative drawings.

In the drawings:

Fig. 1 is an elevational view of a digester embodying the present invention;

Fig. 2 is a fragmentary top plan view of the digester;

2

Fig. 3 is an enlarged fragmentary section taken substantially on the line 3—3 of Fig. 2;

Fig. 4 is a section taken on the line 4—4 of Fig. 1;

Fig. 5 is a fragmentary section taken substantially on the line 5—5 of Fig. 1; and

Fig. 6 is an enlarged section taken on the line 6—6 of Fig. 5.

Referring to the drawings, the reference numeral 10 designates a digester which may advantageously be used in the conversion by bacterial reduction of organic materials into fertilizer for agricultural purposes. The instant digester comprises a series of superposed decks or compartments 12 which, as hereinafter more fully described, are in communication with each other through openings in their respective bottom walls. The material to be converted into fertilizer, hereinafter referred to as "source-material," is introduced into the topmost deck 12' of the digester (Fig. 1), and is caused by plows in the several decks 12 to travel progressively through the latter toward and from the lowermost deck. In the course of its travel through the digester, the source-material is thoroughly mixed and also aerated, all as more fully described hereinafter. Particularly suitable as source-materials for their successful and economic conversion into high-grade fertilizer are organic waste materials, such as garbage, sewage sludge and mill waste, for instance. The source-material is, in conformity with the usual practice, inoculated with certain well-known bacteria which, through bacterial reduction of the material, convert the latter, in the course of its travel through the digester, to useful fertilizer.

The several decks 12 of the digester are characterized in that they are formed as individual units which are particularly well suited for easy transportation and ready assembly at the place of installation of the digester. Each of the decks 12 comprises a bottom wall 14 and a preferably cylindrical side wall 16 which may conveniently be mounted on the bottom wall 14 through inter-mediation of an angle 18 or other fastening means. As best shown in Fig. 3, each deck 12 is open at the top and communicates with the next higher deck through an opening or passage 20 in the bottom wall 14 of the latter. Slotted grates 55 may be provided in these openings 20, if desired.

For their firm support in assembled relation, the decks 12 require at the place of installation of the digester a skeleton frame 21 which comprises, in the present instance, a plurality of angularly spaced uprights 22 that may be anchored

in, or otherwise mounted on, the ground or floor 24. Preferably, the floor 24 is in the form of a concrete base for the digester. The uprights 22 may be in the form of channels to the top ends of which are secured, as by angle brackets 26, for instance, cross braces 28, respectively, which are arranged in the radiating fashion shown in Fig. 2, and have suitably secured to their inner ends, as at 30, a bracket 32 for the support of the top end of an upright, preferably cylindrical, column 34 (Fig. 3). The lower end of the column 34 may conveniently be supported in a bracket 36 on the base 24 (Fig. 1). In the present instance, the braces 26 extend outwardly beyond the uprights 22 and may conveniently be mounted with their outer ends on any suitable structure, such as the walls of a building, for instance, in which the digester is installed.

For a reason described hereinafter, alternate ones of the superposed decks 12 are mounted for rotation relative to the remaining stationary decks. Preferably, the top deck 12' and every other deck 12'' alternating therewith are rotary, while the other decks 12''' are stationary. Each of the rotary decks 12'' is journaled on the central column 34 by means of a combined journal and thrust bearing 40 (Fig. 3), and rides at its outer periphery on a plurality of supporting rollers 42 which are journaled in suitable bearing brackets 44 on at least some of the uprights 22, respectively. In the present instance, the rollers 42 are, as shown in Fig. 4 arranged for each rotating deck 12'' on alternate ones of the uprights 22. To reduce friction between each rotating deck 12'' and the supporting rollers 42 therefor to a minimum, the bottom wall 14 of each of these decks 12'' is provided at its outer periphery with a circularly arranged angle 46 which rides on the adjacent rollers 42.

Each stationary deck 12''' is centered on the column 34 through intermedium of a hub 50 (Fig. 3). The bottom wall 14 of each stationary deck 12''' is at its outer periphery mounted on at least some of the uprights 22 through intermedium of suitable angle brackets 54, respectively (Figs. 1 and 3). The superposed decks 12 of the digester are preferably further supported in the center thereof by means of spacers 56 (Fig. 3) which surround the column 34 and are interposed between the bearings 40 and hubs 50 of successive rotary and stationary decks 12'' and 12''', respectively.

The topmost deck 12' is closed at the top by a cover 60 (Figs. 2 and 3) which may conveniently be mounted on the bracket 32 and braces 28 as at 30 and 64, respectively. For further reinforcement of the skeleton frame 24 of the digester, the cover 60 may additionally be mounted on at least some of the uprights 22 by means of angle brackets 54', respectively.

For reasons described hereinafter, the bottom wall 14 of each, except the lowermost, deck 12, as well as the top cover 60 of the digester, is provided with a depending annular skirt 70 which may conveniently be in the form of an angle that extends with its depending flange into overlapping relation with the side wall 16 of the next lowermost deck 12 (Fig. 3), and may there carry in any suitable manner an annular packing 72 with which effectively to seal the interior of the adjacent deck 12 from the outside thereof, while permitting relative rotation between the latter and said skirt 70. Hence, since the superposed decks 12 are effectively sealed from the outside of the digester as shown in Fig. 3, provisions are

made for the introduction of air into each of the decks 12 for the necessary aeration of the source-material therein. To this end, there is provided in each deck 12 an air-inlet conduit or pipe 80 (Figs. 3 and 5), having perforations 82 for the discharge of air therefrom. The air-inlet conduits 80 in the various decks 12 are in communication with branches 84, respectively, of a common air supply conduit 86 on the outside of the digester. Communication between the air inlet conduit 80 in each stationary deck 12''' and the adjacent branch 84 of the supply conduit 86 is provided through a suitable fitting 92 in the side wall 16 of the deck (Fig. 3). Communication between the air inlet conduit 80 in each rotary deck 12'' and the adjacent branch 84 of the air supply conduit 86 is provided through a suitable fitting 92'' in the depending angle 70 on the next higher stationary deck 12''' (Fig. 3). In the case of the topmost rotary deck 12', the air-inlet conduit 80 therein communicates with the adjacent branch 84 of the air-supply conduit 86 through a suitable fitting 92' in the depending angle 70 on the top cover 60 of the digester. Preferably, the air-inlet conduit 80 in each deck 12 is provided with any conventional type of thermostatic valve 94 which regulates the intake of air in accordance with temperature conditions inside each deck.

For the exhaust from each deck 12 of gases and vapors created in the process of converting the source material into fertilizer, each deck 12 is provided with a perforated exhaust conduit 96 (Fig. 5) which may be arranged, and communicate with an adjacent outside branch 98 of a common exhaust conduit 100, similarly as the air inlet conduit 80 in the same deck. Like the air inlet conduits 80, the exhaust conduits 96 are preferably provided with conventional thermostatic valves 102, respectively, by means of which to regulate the exhaust of the decks in accordance with temperature conditions therein.

It will be understood that as the temperature increases in the respective decks valves 94 and 102 are more fully opened so as to increase the flow of air into the deck and similarly to allow an increase of flow of gases and vapors out of the deck.

The rotary decks 12'' are simultaneously driven, at a relatively low speed, from a prime mover, such as an electric motor 110, for instance, which may suitably be mounted on the floor 24 (Figs. 1 and 2). To this end, the bottom wall 14 of each rotary deck 12'' suitably carries at its outer periphery a ring gear 112 which is in permanent communication with a pinion 114 on an upright shaft 116, journaled in suitable bearing brackets 118 on one of the uprights 22. The lower end of the shaft 116 may be coupled at 120 to the slow shaft 122 of any suitable reduction gearing 124 of the other shaft 126 of which may conveniently be coupled at 128 to the shaft of the motor 110.

The top wall 60 of the digester is provided with an opening 130 (Fig. 2) through which periodically to introduce the source-material through a hopper 132 into the topmost deck 12' substantially at the rate at which the material travels through the successive decks 12 of the digester from the top deck to the bottom deck thereof. The opening 130 in the top cover 60 of the digester may, if desired, be provided with a gate (not shown) which may be kept closed, except when charging the topmost deck 12' of the digester with source-material. For the discharge of the converted material from the digester, the

bottom wall 14 of the lowermost deck 12 is provided with an opening (not shown) and a hopper 136 (Fig. 1). If desired, the discharge opening in the lowermost deck 12 may be provided with a gate (not shown) which may be kept closed, except during the discharge of the converted material from the digester. For inspection, test and other purposes, each deck 12 may in its side wall 16 be provided with a hatch 140 (Figs. 1 and 4) which may normally be closed by a hinged cover 142.

For thoroughly mixing the source-material and causing its flow through the digester, as well as for providing for its uniform aeration, there are provided in each deck 12 a plurality of plows 150 (Figs. 3 and 4). The plows 150 are in the present instance, arranged in each deck 12 in four groups g of a predetermined number each. The plows 150 of each group g in each deck 12 are carried by a bracket 152, mounted at 154 on the bottom wall 14 of the next higher deck 12 (Fig. 3). The plough-carrying brackets 152 in the topmost deck 12' are mounted on the top cover 60 of the digester as shown in Fig. 3. The plows 150 in each and all groups g may be of identical construction, each comprising a knife shank 160 which terminates at its lower end in a laterally projecting scoop 162 (Figs. 3 and 6). The upper end 164 of each plow 150 is preferably cylindrical and journaled in its bracket 152 in the manner shown in Fig. 6. Suitably mounted on the cylinder end 164 of each plow 150 is a worm gear 166 which is in permanent mesh with a worm 168 on a shaft 170, journaled with its opposite ends in the corresponding bracket 152 (Fig. 5). The worm gears 166 on the plows 150, respectively, of each group g may be received in recesses 172, respectively, in the corresponding bracket 152 and bear against thrust washers 174, respectively. The outer end of the worm shaft 170 in each plow-carrying bracket 152 is provided with a hand wheel 178 for turning the worm shaft 170 and thereby causing angular adjustment of the associated plows 150, as will be readily understood. For ready adjustability of the plows 150 in each deck 12, the worm shafts 170 therein preferably extend to the outside thereof and there carry their respective hand wheels 178. To this end, the worm shafts 170 in each deck 12 extend through the associated top angle 70 thereof in the manner shown in Fig. 3. In order that the brackets 152 and associated plows 150 in each stationary deck 12'' will, on their rotation with the next higher, rotary deck 12'', clear the fixed air-inlet and exhaust conduits 80 and 96, respectively, in the stationary deck, these conduits are located below the adjacent brackets 152 and outside the path of rotation of the adjacent outermost plows 150 (Figs. 3 and 5).

Simultaneous angular adjustment of the plows of any group g in any deck 12 not only brings the scoop ends 162 thereof into different scooping relation with the source-material therein, but brings also the broadside of the knife shank 160 of each of these plows more or less into confronting relation with the source-material in the deck. In the example shown in Figs. 3 and 4, the plows 150 in any deck 12 are so adjusted that the relatively sharp edges e of the knife shanks 160 thereof slice with minimum resistance into the source-material, while the scoop ends 162 of these plows have a maximum scoop action on the material for the flow of the latter at a maximum rate. More thorough mixing of the source-

material and a flow of the same at a slower rate is readily accomplished by differently adjusting the plows, as will be readily understood. It also appears from Fig. 3 that the scoop ends 162 of the plows in consecutive decks 12 project in opposite directions, the plow being thus adjusted in order to direct the flowing source-material in the various decks 12 toward the discharge passages 20 therein, respectively, which are arranged in a staggered fashion as more fully explained hereinafter. Inasmuch as the plows 150 in each deck are, through intermediation of the brackets 152, carried by the bottom walls 14 of the next higher deck and by the top cover 160 of the digester, it will readily be understood that the plows in each stationary deck 12'' move with the next higher rotary deck 12'', while the plows in each rotary deck 12'' are stationary. Thus, while mere rotation of the rotary decks 12'' of the digester brings about agitation of the source-material throughout the digester, such agitation of the source-material in each rotating deck 12'' is caused by the impingement of the material therein against the adjacent stationary plows, while agitation of the source-material in each stationary deck 12''' is caused by the motion of the plows therein against the material. In order that the source-material in each deck 12 may thoroughly be mixed by the plows therein before it is transferred to the next lowermost deck, the discharge passages 20 in the several decks are preferably staggered in the fashion shown in Fig. 3, i. e., are alternately arranged near the inner and outer peripheries of the bottom walls 14 of consecutive decks 12. In order to afford maximum protection to the journal bearings 40 of the rotary decks 12'' from the corrosive source-material in the digester, there are mounted at 180 on the bottom walls 14 of the decks 12 cylindrical baffles 182, respectively, which keep the source-material from these bearings. Each deck may be made of any suitable material, for example, but without limitation, they may be made of any suitable corrosion-resistant alloy steel.

The instant digester secures several important advantages. Thus, the construction of the several decks 12 of the digester as individual units permits their easy transportation and ready assembly at the place of the installation of the digester. By rotating the alternate decks 12'' of the digester, and mounting the plows in the latter as described, the plows require no further provisions, but rely for the performance of their function solely on the motive force of the alternate rotating decks 12''. In conclusion, the construction of the several decks 12 of the digester in individual units not only facilitates the transportation and installation of the digester, but also greatly simplifies the overall digester structure. Moreover, by solely relying on the motive force of the rotating decks 12'' of the digester for the agitation of the source-material therein, and in view of the drive of these rotating decks 12'' at their outer peripheries, the power consumption requisite for the agitation and flow of the source-material in the digester by the plows therein is extremely low. The low power consumption by the instant digester for its performance is quite important, since the source-material requires for its travel through the digester under constant agitation several days during which the rotating decks 12'' will ordinarily be driven continuously.

While we have shown and described the pre-

ferred embodiment of our invention, it will be understood that various changes may be made in the present invention without departing from the underlying idea or principles of the invention within the scope of the appended claims.

Having thus described our invention what we claim and desire to secure by Letters Patent, is:

1. A material digester for the conversion of organic materials into fertilizer, comprising a plurality of containers disposed in succession about a common axis, said containers having a bottom wall and affixed side walls, said succession of containers being formed as individual units and sealed from the outside of the digester, each container having a passage for the displacement of material therefrom into the next lower, container and alternate ones of said containers being mounted for rotation in their superposed relation with the other containers, plows dependingly carried by said containers, respectively, and projecting into the next lower containers, respectively, for displacing the material in the respective containers toward the respective passages therein on relative rotation between said rotary and other containers, means for driving said rotary containers and each of said containers having an air inlet, and valve means for controlling the passage of air into said containers, respectively, through their respective air inlets, and means responsive to the temperature in the interior of said containers, respectively, during the digestion process for operating said valve means.

2. A material digester for the conversion of organic materials into fertilizer, comprising a plurality of containers disposed in succession about a common axis, said containers having a bottom wall and affixed side walls, said succession of containers being formed as individual units and sealed from the outside of the digester, each container having a passage for the displacement of material therefrom into the next lower container and alternate ones of said containers being mounted for rotation in their superposed relation with the other containers, plows dependingly carried by said containers, respectively, and projecting into the next lower containers, respectively, for displacing the material in the respective containers toward the respective passages therein on relative rotation between said rotary and other containers, means for driving said rotary containers and each of said containers having an outlet for gases and vapors, a control valve for each of said outlets, and means responsive to the temperature in the interior of said containers during the digestion process for operating said outlet control valves.

3. A material digester for the conversion of organic materials into fertilizer, comprising a series of superposed containers, said containers having a bottom wall and distinct side walls, each container having a passage for the displacement of material therefrom into the next lower container and alternate ones of said containers being mounted for rotation in their superposed relation with the other containers, plows adjustably carried by said containers, respectively, and projecting into the next lower containers, respectively, for displacing the material in the respective containers toward the respective passages therein on relative rotation between said

rotary and other containers, means for driving said rotary containers, and separate means for adjusting said plows in said containers, respectively, for varying the rate at which the material in the respective containers is displaced by the respective plows.

4. A material digester for the conversion of organic materials into fertilizer, comprising a series of superposed containers, said containers having a bottom wall and distinct side walls, each container having a passage for the displacement of material therefrom into the next lower container and alternate ones of said containers being mounted for rotation in their superposed relation with the other containers, plows adjustably carried by said containers, respectively, and projecting into the next lower containers, respectively, each of said plows having a scoop-like end and being rotatably adjustable into angular positions in which the scoop-like end thereof displaces different amounts, respectively, of the material in the respective container on relative rotation between the latter and the next higher container, means for driving said rotary containers, and separate means for adjusting said plows in said containers.

5. A material digester of the character described, comprising superposed containers, said containers having a bottom wall and side walls, each having a passage for the displacement of material therefrom into the next lower container, and alternate ones of said containers being mounted for rotation in their superposed relation with the other containers, plows adjustably carried by said containers, respectively, and projecting into the next lower containers, respectively, for displacing the material in the respective containers toward the respective passages therein on relative rotation between said rotary and other containers, each of said plows being rotatably mounted on its respective container for angular adjustability of the former, means for driving said rotary containers, separate devices for adjusting said plows in said containers, respectively, for varying the rate at which the material in the respective containers is displaced by the respective plows, each of said devices comprising a worm gear on the associated plow, a shaft rotatably mounted in, and projecting with its outer end to the outside of, the container on which said associated plow is mounted, and being provided with a worm in permanent mesh with said worm gear, and means on the outer end of said shaft for turning the latter.
